DESIGN FOR A LAMP SUPPORTING ATTACHMENT STRUCTURE FOR CHIMNEYS AND THE LIKE

Clyde K. Lamb, Cleveland, Ohio

Application October 19, 1943, Serial No. 111,423

Term of patent 14 years

(Cl. D48—20)

To all whom it may concern:

Be it known that I, Clyde K. Lamb, a citizen of the United States, residing at Cleveland, in the county of Cuyahoga and State of Ohio, have invented a new, original, and ornamental Design for Lamp Supporting Attachment Structure for Chimneys and the Like, of which the following is a specification, reference being had to the accompanying drawing, forming a part thereof, in which:

Fig. 1 is an elevational view of the lamp supporting attachment structure for chimneys and the like showing my new design;

Fig. 2 is an enlarged top plan view; and
Fig. 3 is an enlarged side elevational view of the top portion thereof.

The dotted line illustration in the drawing figures is for illustrative purposes only.

I claim:

The ornamental design for a lamp supporting attachment structure for chimneys and the like, substantially as shown and described.

CLYDE K. LAMB.
